(57) **CLAIM**

The ornamental design for a smoke barrel, as shown and described.

DESCRIPTION

This application is being filed contemporaneously with application for U.S. Design application No. 29/832,869, filed Mar. 30, 2022, entitled Smoke Lid, which is hereby incorporated by reference herein.

FIG. 1 is an upper front perspective view of a smoke barrel embodying our design, with the smoke barrel including a barrel body, a shiftable barrel door, and barrel rings, and with the broken lines depicting features of a barrel lid that forms no part of the claimed design;

FIG. 2 is an upper front perspective view of the smoke barrel similar to FIG. 1, but showing the barrel door opened to permit access to the barrel interior;

FIG. 3 is a lower rear perspective view of the smoke barrel shown in FIG. 1;

FIG. 4 is a lower front perspective view of the smoke barrel shown in FIGS. 1 and 3;

FIG. 5 is an upper rear perspective view of the smoke barrel shown in FIGS. 1, 3, and 4;

FIG. 6 is a front elevational view of the smoke barrel shown in FIGS. 1 and 3-5;

FIG. 7 is a right side elevational view of the smoke barrel shown in FIGS. 1 and 3-6, with the left side elevational view being a mirror image thereof;

FIG. 8 is a rear elevational view of the smoke barrel shown in FIGS. 1 and 3-7;

FIG. 9 is a top view of the smoke barrel shown in FIGS. 1 and 3-8; and,

FIG. 10 is a bottom view of the smoke barrel shown in FIGS. 1 and 3-9.

The broken lines shown in the drawings show portions of the smoke barrel that form no part of the claimed design.
